DESIGN FOR A LAMP

Victor Weidner, Port Washington, and Fenick
A. Vogel, New York, N. Y.

Application June 5, 1937, Serial No. 69,704

Term of patent 14 years

To whom it may concern:

Be it known that we, Victor Weidner and Fenick A. Vogel, citizens of the United States, residing at Port Washington and New York, respectively, in the counties of Nassau and New York, respectively, and State of New York, have invented a new, original, and ornamental Design for a Lamp, of which the following is a specification, reference being had to the accompanying drawing, forming part thereof.

Fig. 1 of the drawing is a front view, in elevation, of a lamp, showing our new design; and
Fig. 2 is a side view thereof.

We claim:

The ornamental design for a lamp, as shown.

VICTOR WEIDNER.
FENICK A. VOGEL.
